WIRE STRETCHING TOOL

Gilbert O. Hunt, Lakeview, Mont.

Application April 5, 1935, Serial No. 14,908

2 Claims. (Cl. 140—102.5)

This invention relates to an improved wire stretching tool which is particularly designed for tightening slackened fence wires or uniting and stretching broken strands.

One object of the invention is to provide a wire stretching tool which may be readily engaged with a fence or other wire at any point along its length for effecting the stretching or tightening thereof.

Another object of the invention is to provide a wire stretching tool having a loop which is provided with angularly disposed arms terminating in hooks, which arms are arranged in such a manner that turning of the loop will permit selective engagement of the hooks with the wire at each quarter turn of the loop so that the wire may be drawn very taut with facility and may be held at the desired degree of tautness.

A further object of the invention is to provide a device of this character wherein the hooks employed are formed with inclined end walls so that a wire coming in engagement with said hooks may readily slide over the inclined walls and drop into place behind the hooks.

A further object of the invention is to provide a wire stretching tool wherein forceps are employed with the loop, which forceps are provided with a latch for retaining said forceps in position on the loop during the tightening operation.

And the invention has as a still further object to provide a wire stretching tool which may be manufactured cheaply and which will be durable in use.

Other and incidental objects not specifically mentioned hereinbefore will become apparent as the description of the invention proceeds.

In the drawing forming a part of my application:

Figure 1 is a top plan view of the device as it would appear with a portion of wire twisted on the loop thereof.

Figure 2 is a longitudinal sectional view on the line 2—2 of Figure 1, looking in the direction indicated by the arrows.

Figure 3 is a fragmentary sectional view on the line 3—3 of Figure 2, looking in the direction indicated by the arrows.

Figure 4 is an enlarged fragmentary perspective view showing the recess formed in one of the jaws of the forceps.

Figure 5 is a fragmentary plan view showing a slightly modified clamping structure for the forceps employed.

Referring now more particularly to the accompanying drawing, the numeral 1 indicates, in gen-

eral, a pair of forceps or tongs which comprise companion handle members 2 and 3 pivotally connected near corresponding ends by a pin 4. Companion jaws 5 and 6 are formed on the handle members and said jaws are provided with opposed semi-circular recesses which are indicated in dotted lines by the numeral 7 opening at the corresponding ends of the jaws. As better seen in Figures 1 and 2 of the drawing, the opposite corresponding end portions of the handle members, indicated at 8 and 9, are bent to project in opposite directions and lie in adjacent arcs so that when the handle members are shifted, the portions 8 and 9 will be disposed in engagement, or in close spaced relation to each other, throughout part of their shifting movement. It will be understood that the bent portions 8 and 9 serve as guides and cooperate with the pin 4 for preventing relative movement of the jaws 5 and 6 during the wire stretching or tightening operation. When the jaws are closed, the portions 8 and 9 provide handles affording sufficient leverage so that turning of the forceps, and the loop carried therein to be hereinafter described, may be readily effected.

Welded or otherwise secured to the bent portion 8 of the handle member 3 is a flat metal U-shaped yoke 10 which extends freely about the bent portion 9 of the handle member 2. Carried between the arms of the yoke is a latch, shown in general by the numeral 11. The latch comprises a handle 12 which extends between the handle members 2 and 3, and a tapered wedge 13 which is formed with serrated faces 14. The latch is mounted in such manner, that, when the handle 12 is shifted, the wedge 13 will be engaged between the portions 8 and 9, so that relative movement of said portions, with consequent locking of the forceps, will take place. The wedge is mounted on the yoke by means of a pin 15 and is spaced between the arms of the yoke by bushings 16. While, in the present instance, I have shown the yoke as being secured to the portion 8, it will be understood that it may be just as readily secured to the portion 9.

Normally associated with the forceps is a loop which is indicated generally by the numeral 17. The loop is substantially U-shaped and comprises parallel portions 18 and 19 which are connected by a bight 20. As will be seen from the drawing, the bight is normally carried between the jaws 5 and 6, in the recesses 7 therein, and is adapted to project forwardly from the jaws. The parallel portions 18 and 19 are bent and projected to define arms 21 and 22 which are disposed at right

angles to each other and terminate in hooks 23 and 24 bent at right angles to the arms and formed with inclined walls or end faces 25 and 26.

- In operation, the loop is placed on a length of 5 wire to be tightened or stretched, with the wire extending between the parallel portions 18 and 19. The forceps, which carry the bight of the loop, are tightened so that said loop is effectually confined within the recesses 7 of the jaws 5 and 6. 10 The end portions 8 and 9 are locked in position by the latch 11 so that the forceps will be effectually locked on the loop. The portions 8 and 9 are then grasped and the forceps and loop twisted for winding the wire about the portions 18 and 15 19. When it is desired to lock the loop in any given tightened position, the loop is shifted for permitting the wire, indicated by the numeral 21, to slide over the inclined wall 26 of the hook 24 and engage therebehind for effectually retaining 20 the wire in the desired locked position. When it is desired to further tighten the wire, the loop may again be rotated and the hook 23 engaged with the wire in the same manner as the hook 24. Inasmuch as the arms 21 and 22 are disposed 25 at right angles to each other, a wire may be locked at each quarter turn of the loop. This will permit effective tightening of the wire to maximum tautness. After the wire has been properly tightened, the latch 11 is shifted for removing the 30 wedge 13 from between the portions 8 and 9 so that said portions may be permitted to shift. By shifting the handle members 2 and 3, the jaws 5 and 6 are opened for freeing the loop therefrom. As the hooks are each provided with an inclined 35 wall, the wire will be permitted to readily slide over the wall and behind the hook without danger of slipping.

Referring now to the modification of the invention as illustrated in Figure 5 of the drawing, 40 the numerals 28 and 29 indicate companion handle members. The handle member 28 is provided with a series of longitudinally disposed spaced notches 30 which are arcuate in shape and are adapted to receive a bight portion of an elliptical locking loop 31 which is engaged about the 45 members 28 and 29 and is shiftable along said members for locking the same against relative

movement when it is desired to lock the jaws carrying the wire carrying loop during a stretching or tightening operation. Aside from the foregoing modification, the invention operates in a like manner with that of the preferred form. 5

When it is desired to splice the ends of broken wires, the procedure is as follows: First form a loop on the end portion of the wire disposed to the right hand, holding the forceps in horizontal position with the loop 17 therein. The wire to 10 the left hand is then drawn up as tight as convenient and is inserted between the parallel jaws of the forceps and is turned back underneath said forceps. The surplus wire may be cut away and the remainder of the splicing operation is carried 15 on in the same manner as is employed in tightening slack wire.

It is thought that, from the foregoing, it will be understood that I have provided a wire stretching or tightening tool which will be simple 20 in construction and easy to operate, and which may be manufactured to retail at a reasonable figure.

Having thus described the invention, what I claim is:

1. In a wire stretching tool, a loop having parallel portions connected by a bight, said parallel portions being bent and projected at right angles to each other to define arms terminating in hooks, said loop being adapted to 30 receive a wire between the parallel portions thereof for tightening by rotation of the loop, and one of said hooks engaging the wire after the tightening operation for retaining the wire tightened.
2. In a wire stretching tool, a loop having side 35 portions connected by a bight, said side portions being bent and projected at right angles to define arms terminating in hooks, said hooks being bent at right angles to the arms and being formed with inclined walls and said loop being adapted to receive a strand of wire to be stretched and said wire being stretched by the rotation of the loop on its longitudinal axis, the wire being engageable over the inclined walls and behind one of the hooks for retaining the wire stretched 40 after the stretching operation.

GILBERT O. HUNT.
